UNITED STATES PATENT OFFICE.

WILLIAM F. JOHNSTON, OF PHILADELPHIA, PENNSYLVANIA.

INKSTAND.

SPECIFICATION forming part of Letters Patent No. 614,869, dated November 29, 1898.

Application filed April 16, 1898. Serial No. 677,789. (No model.)

To all whom it may concern:

Be it known that I, WILLIAM F. JOHNSTON, a citizen of the United States, residing at the city of Philadelphia, in the county of Philadelphia and State of Pennsylvania, have invented certain new and useful Improvements 5 in Inkstands, of which the following is a specification.

My invention relates to that class or type 10 of ink stands or holders wherein the interior of the well of the holder is provided with a removable shell into which the ink is adapted to flow, and in such connection it relates more particularly to the construction and arrangement 15 of such an ink stand or holder.

The principal object of my invention is to provide a simple, cheap, and effective ink stand or holder having a removable shell into which the ink is adapted to percolate through 20 a suitable perforation or perforations and having a removable cap adapted to be secured onto the neck of the holder to hold the shell in position, the said cap having a funnel-shaped projection extending downward 25 into the shell for the reception of the pen, and all the parts of the holder or inkstand being arranged so that the same may be caused to assume a reversed position, if desired, without spilling the ink.

My invention, stated in general terms, consists of an ink stand or holder constructed and arranged in substantially the manner 30 hereinafter described and claimed.

The nature and scope of my invention will 35 be more fully understood from the following description, taken in connection with the accompanying drawings, forming part hereof, in which—

Figure 1 is a perspective view of an ink 40 stand or holder embodying the main features of my invention. Fig. 2 is a cross-sectional view of the same; and Fig. 3 is a view similar to Fig. 2, but illustrating the ink stand or holder in an inverted position.

Referring to the drawings, *a* represents an 45 ink-well of ordinary form and preferably glass. The interior *a'* of the well is preferably rectangular in cross-section and serves as the main ink-reservoir. The well *a* is provided with a threaded neck *a²*, upon which 50 is adapted to be supported an elastic gasket

or washer *b*, which in turn is adapted to support a shell *d*, as hereinafter more fully explained. The shell *d* is preferably cup-shaped and terminates in a tubular extension or projection *d'*, which is preferably closed at its base *d²*, except for one or more perforations *d³*. The shell *d* and its tubular extension *d'* traverse the interior of the neck *a²* and reservoir *a'*, and the base *d²* extends to within 60 a short distance from the floor *a³* of the well *a*. The upper end of the shell *d* is flanged, as at *d⁴*, and this rim or flange *d⁴* rests upon the gasket or washer *b*, which supports the shell *d* in operative position in the well. 65 Upon the neck *a²* of the well *a* is adapted to be screwed a cap *e*, which when advanced will clamp the rim or flange *d⁴* and washer *b* tightly against the neck *a²* to form a liquid-tight seal. The cap *e* has a funnel-shaped 70 tube or opening *e'* extending down through the shell *d* and having its lower open end *e²* terminating, preferably, at about the upper end of the tubular extension *d'* of the shell.

In operation the reservoir *a'* of the ink-well 75 *a* is first filled to required height. The shell *d* and washer *b* are then placed in position and the cap *e* finally screwed down upon the neck *a²*. When thus assembled, ink will percolate through the perforation or perforations *d³* in 80 the base *d²* of the shell *d* until the ink substantially fills the shell *d* to a height about on a line with the base of the funnel *e'* of the cap *e*, as shown. When the ink reaches this height, no matter how high it may be in the 85 reservoir *a'*, it will no longer flow into the shell *d*, for the reason that the ink seals the opening of the funnel *e'*, and thus renders the interior of the shell *d* air-tight. The stand thus constructed and arranged can readily be 90 turned to any position and even reversed or upset, as shown in Fig. 3, without permitting the ink to escape from the stand. In cleaning or filling the stand all the parts are rendered quickly accessible by simply unscrewing the 95 cap *e* from the neck *a²* of the well.

Having thus described the nature and object of my invention, what I claim as new, and desire to secure by Letters Patent, is—

An inkstand, comprising a well or reservoir provided with a threaded neck, an elastic washer supported on said neck, a shell ex-

tending into the reservoir and provided with a lower tubular extension, the base whereof is closed and perforated, a rim formed on the upper end of said shell and resting on said washer, and a cap adapted when advanced on said neck to clamp the washer and rim of said shell down upon said neck to form an air-tight joint therewith and said cap having a funnel-shaped tube extending through said shell down to the upper end of the tubular

extension of said shell, substantially as and for the purposes described.

In testimony whereof I have hereunto set my signature in the presence of two subscribing witnesses.

WILLIAM F. JOHNSTON.
